Inventor:
Lionel M. Woolson,

By Milton S. Tiffey, Jr.

UNITED STATES PATENT OFFICE.

LIONEL M. WOOLSON, OF DETROIT, MICHIGAN, ASSIGNOR TO PACKARD MOTOR CAR COMPANY, OF DETROIT, MICHIGAN, A CORPORATION OF MICHIGAN.

HYDROCARBON MOTOR.

Application filed June 11, 1920. Serial No. 388,129.

To all whom it may concern:

Be it known that I, LIONEL M. WOOLSON, a citizen of the United States, and resident of Detroit, Wayne County, State of Michigan, have invented certain new and useful Improvements in Hydrocarbon Motors, of which the following is a specification.

This invention relates to hydrocarbon motors, and particularly to means for heating the mixture passing from the carburetor to the motor cylinders.

The application is in part a division of my pending application Serial No. 323,627, filed September 13, 1919, and in part a continuation of my Patent No. 1,448,651, dated March 13, 1923.

The invention relates more specifically to the combustion device which is less fully illustrated in said pending applications, and it comprises a body having inlet and outlet openings and having means for receiving a spark plug and an observation window. At the inlet opening there is a means for holding a screen for breaking up the combustible mixture as it enters the device.

Preferably the inlet and outlet openings of the combustion device are at opposite ends thereof, and, as shown in the particular form illustrated, the spark plug and observation window openings are in the sides of the device and in line with each other.

Referring to the drawings which illustrate a preferred form of the invention, which drawings form a part of this specification,

Figure 1 is a sectional view through the device;

Figure 2 is a section substantially on the line 2—2 of Figure 1;

Figure 3 is an elevation of the device illustrated in Figure 1; and

Figure 4 is a top view of the device.

In these drawings the body 10 is hollow and is of substantially cylindrical form, being somewhat longer than its diameter. Its interior forms a combustion chamber 11 and at one end there is provision for an inlet and at the other end an outlet. As shown, the inlet 12 is formed in an elbow 13 which is connected to a pipe 14 and is provided with an adjusting valve 15. The elbow 13

is connected to the body of the device by being threaded into a hollow nut 16, which nut is also threaded into the inlet end of the body of the device against a screen 17 which is provided for breaking up the particles of mixture into finer form.

At the outlet end of the body of the device there are lateral ears 18 by which the device may be secured to a support with screws 19, as shown. For properly positioning the body on the support, it is extended as in the form of a boss 20, this boss entering an opening 21 in the support 22. This support 22 may be the outer wall of a jacket surrounding the intake header of the motor, and in this case the interior of the combustion device will communicate with the interior of this jacket by an outlet opening 23 extending through the boss 20.

The combustion device is also provided with means for supporting a spark plug or other igniter and an observation window, and in the form shown the body is made with bosses 24 and 25 extending laterally from the sides of the body and preferably in line with each other. The boss 24 is interiorly threaded to receive a spark plug 26, the points 27 of which extend well into the interior of the combustion device, and the boss 25 has an interior shoulder 28 against which a glass or other window 29 rests. A hollow nut 30 retains the observation window in position. By this arrangement of spark plug and window the conditions inside the combustion device may be readily observed, both as to whether or not the spark plug is firing and whether the correct mixture is being drawn into the combustion chamber.

It will be seen that the device provides an extremely compact arrangement of the various functional elements of a combustion heating means and it may be made and sold as a unit which requires only that its inlet and outlet be suitably connected with the motor and its spark plug connected with the ignition system.

The device is, of course, capable of modification in various ways without departing from the spirit of the invention.

Having thus described my invention,

what I claim and desire to secure by Letters Patent is:

1. A combustion device having a screened inlet opening at one end, an outlet opening, and lateral aligned openings for a spark plug and window respectively.
2. A combustion device having an inlet opening comprising a downwardly extending passage, means near the lower end of

said passage for breaking up the mixture, said device also having a lateral opening for a spark plug, a spark plug in said lateral opening and extending into the device to a point beneath said passage, an outlet for said device, and an observation window.

In testimony whereof I affix my signature.

LIONEL M. WOOLSON.
